FLASH GUN SOCKET

Robert F. Rau, Ann Arbor, Mich., assignor to Sylvania
 Electric Products Inc., a corporation of Delaware
 Filed Mar. 9, 1959, Ser. No. 798,249
 5 Claims. (Cl. 339—45)

This invention relates to flash guns for use with cameras and is particularly concerned with special lamp socket structure for such guns.

In its preferred embodiment the invention will be described in a flash gun wherein the socket assembly is adapted to receive and eject the lamp in axial movements of the latter. The socket assembly comprises essentially a spring biased pivoted section adapted to latch with the lamp base, a centered contact and ejector spring and a linkage for actuating the pivoted latch member, all in novel association.

It is the major object of the invention to provide a novel flash gun socket having a special lamp base latching structure.

A further object of the invention is to provide a novel flash gun socket structure wherein a pivoted section of the socket has latching engagement with a lamp base and a special lever is interposed between the pivoted section and a manual release member.

Further objects of the invention will appear as the description proceeds in connection with the appended claims and the annexed drawings wherein:

FIGURE 1 is a section showing the flash gun with the socket in side elevation;

FIGURE 2 is a front view of the upper part of the flash gun partly in section and broken away to show socket detail;

FIGURE 3 is a front view of the casing with the reflector and socket removed;

FIGURE 4 is an enlarged section on line 4—4 of FIGURE 2 showing socket details;

FIGURE 5 is an enlarged fragmentary section on line 5—5 of FIGURE 3;

FIGURE 6 is a side elevation of the socket and latch subassembly; and

FIGURE 7 is a top plan view of the socket assembly removed from the flash gun.

The flash gun comprises a molded plastic casing 11 having a bottom battery introducing opening closed by a screwed-on metal cap 12. As shown in FIGURE 3 the casing has a front aperture 13 surrounded by a flat generally annular surface 14 in which are disposed an upper pair of threaded apertures 15 and a lower pair of threaded apertures 16. A centered recess 17 extends back into the casing from surface 14 to a surface 18 on an integral transverse wall 19 within the casing. Recess 17 communicates with the battery compartment through a slot 21. The upper end of recess 17 is a flat surface 22 that is perpendicular to surface 14 which in turn is perpendicular to the socket axis.

A rigid socket frame 23 made of a single piece of sheet metal is secured upon the casing. Frame 23 comprises a rectangular tubular body 24 formed at its forward end with an integral support flange 25 that projects downwardly and forwardly therefrom. Flange 25 bridges the open front end of recess 17 and seats at opposite ends in recesses 26 in surface 14 of such depth that flange 25 is flush with surface 14. Suitable screws 27 pass through flange 25 into apertures 16 to rigidly mount the socket frame 23 on the casing with flange 25 disposed in recesses 26.

The upper portion of hollow socket frame 23 is open upwardly except for a forward bridge 28, which is formed by tabs extending from the adjacent side walls. Rearwardly of bridge 28 each body side wall has in sequence

2

a rectangular notch 29, a lug 31 and a fulcrum notch 32. A rear lug 33 projects above the level of lug 31 and has a forwardly directed face 34 above the level of lug 31, a downwardly and rearwardly inclined guide face 35 within the notch and a forwardly facing fulcrum portion 35' at the inner rear end of notch 32.

10 A socket latch member 36 is pivoted on the frame 23. Member 36 is a single piece of sheet metal having a forwardly disposed lamp base engaging portion 37 and a downwardly displaced rear step portion 38 terminating in a tail 39. Portion 37 is formed on the sides with oppositely extending side lugs 41 adapted to be received in socket notches 29, notches 42 adapted to embrace socket lugs 31 and side lugs 43 adapted to be received in fulcrum notches 32 of the socket.

15 The latch member 36 is mounted on socket frame 23 by disposing lugs 43 against socket faces 34 and rocking the latch down to dispose lugs 43 within notches 32, being guided by faces 35. Thus lugs 43 effectively pivot the latch member 36 about fulcrums 35' and the lugs 41 abut in notches 29 to limit counter clockwise rocking of latch member 36.

20 The forward portion 37 of the latch member 36 is formed to provide depending spaced lips 44, the forward lip having an inclined front cam face 45. Preferably lips 44 are formed by displacing metal down out of the flat latch portion 37, providing a slot 46 between the lips (FIGURE 7).

25 A compression spring 47 biases latch member 36 into the solid line position of FIGURE 4. Spring 47 is a sheet metal spring having a flat base 48 seated against casing surface 22 and a spring arm 49 which terminates in a rounded end 51 bearing slidably against the top surface of latch member 36 just forwardly of the pivotal connection between the latch member and the socket.

30 The top wall of casing 11 is formed with a recess 52 in which a push button 53 is slidably mounted. The lower end 54 of button 53 within the casing is larger than recess 52 to prevent withdrawal through the recess and bears against step 38 of the latch member 36. When the projecting part of button 53 is pressed to depress it to the dotted line position of FIGURE 4 the latch member 36 is rocked against the pressure of spring 47 to its dotted line position. It will be noted that tail 39 will strike the top of wall 19 to limit rocking of latch 36.

35 A center contact member 55 has an intermediate section 56 anchored onto the face 18 of wall 19 as by screw 57, a lower spring arm 58 extending into the battery compartment to engage the upper terminal of a battery, and an upper spring arm 59 extending up into the interior of the hollow socket frame body. Arm 59 ends in a rough surfaced terminal 61 centered on the socket axis.

40 When the flash bulb, which is of the type known as M-2 having a cylindrical base 62 formed with a rear continuous circumferential recess 63 and an annular flange 64, is thrust into the socket the flange 64 first engages cam face 45 to slightly rock latch 36 clockwise against the force of spring 47 sufficiently to enable the flange to pass front lip 44 and become disposed in slot 46. There the lamp base is locked against axial movement and its center contact 65 has engaged terminal 61 to compress contact spring arm 59.

45 A reflector 66 is secured in centered relation with the socket axis, with an internal flange 67 mounted against surface 14 and held there by upper screws 68 entering apertures 15 and the same screws 27 that hold socket frame flange 25.

50 When the socket is empty a lamp may be mounted on it in operative relation simply by thrusting the base axially into socket frame body 24 until latched by member 36. The center contact 65 establishes one side of the electrical circuit with contact spring 55, and the metal socket frame 23 is part of the other side of the circuit.

After use the bulb is speedily ejected and thrown clear of the reflector when the operator presses down on button 53. This unlatches slot 46 from the base flange 64 and the powerful spring arm 59 expands to eject the bulb.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a flash gun, a casing having an opening, and a generally tubular lamp receiving socket structure disposed within the casing at said opening comprising a socket member rigidly mounted on said casing and open forwardly in registration with said opening, said member being open rearwardly into the interior of said casing, a contact and ejector spring mounted within the casing and having a portion adjacent the rear opening of said socket member adapted to be engaged and compressed by the base of a lamp thrust into the front opening of said socket member, a latch member rockably mounted on said socket member, spring means biasing said latch member toward lamp base latching position on said socket member, means comprising a transverse slot and coacting opposed lips depending at said slot on the forward portion of said latch member extending toward said socket member and adapted to engage and interlock with the base of a lamp thrust into the front opening of said socket member, and a manually operable member accessible exteriorly of said casing and extending through said casing into contact with a rear portion of said latch member for rocking said latch member to lamp base release position against the force of said spring means to thereby permit said ejector spring to eject said lamp forwardly away from said casing.

2. In a flash gun, a casing having an opening, and a generally tubular lamp receiving socket structure disposed within the casing at said opening comprising a socket member rigidly mounted on said casing and open forwardly in registration with said opening, said member being open rearwardly into the interior of said casing, a contact and ejector spring mounted within the casing and having a portion adjacent the rear opening of said socket member adapted to be engaged and compressed by the base of a lamp thrust into the front opening of said socket member, said member having an upper opening and being formed with laterally aligned fulcrum notches at opposite sides of said opening, a latch lever rockably mounted on said socket member to extend over said upper opening and having side lugs extending into said notches, spring means reacting between the casing and latch member biasing said latch lever toward lamp base latching position on said socket member, means on said latch lever adapted to engage and interlock with the base of a lamp thrust into the front opening of said socket member, and a manually operable plunger slidably mounted on said casing and accessible exteriorly of said casing engaged with said latch lever for rocking said latch lever to lamp base release position against the force of said spring means to thereby permit said ejector spring to eject said lamp forwardly away from said casing.

3. In a flash gun, a casing having an opening, and a generally tubular lamp receiving socket structure disposed within the casing at said opening comprising a rigid socket frame having a depending flange secured on said casing at said casing opening and open forwardly in registration with said casing opening, said frame being open rearwardly and upwardly into the interior of said casing, a lateral

bridge rigid with said frame extending across said upper opening at the forward part of the frame, a contact and ejector spring mounted within the casing and having a portion adjacent the rear opening of said socket frame adapted to be engaged and compressed by the base of a lamp thrust into the front opening of said socket frame, means providing laterally aligned upwardly open fulcrum notches in said frame, a latch lever rockably mounted on said socket member by means of lugs laterally projecting into said notches, spring means biasing said latch member to overlie said upper frame opening to dispose it in lamp base latching position on said socket frame, means on said latch lever adapted to engage and interlock with the base of a lamp thrust into the front opening of said socket frame, and manually operable means accessible exteriorly of said casing for engaging and rocking said latch lever to lamp base release position against the force of said spring means to thereby permit said ejector spring to eject said lamp forwardly away from said casing.

4. In a flash gun, a casing, a socket member rigidly mounted within said casing and forwardly open to receive the base of a lamp thrust axially thereto, said member having an upward opening and being formed with laterally aligned upwardly open fulcrum notches at opposite sides of said opening, a latch member extending over said opening and having side lugs disposed in said notches whereby the latch member is fulcrumed on said socket member, a compression spring within the casing bearing directly on said latch member whereby the latch member is urged against said socket member and spring biased into lamp base latching position, and a forwardly facing cam surface on said latch member adapted to be contacted by said lamp base upon introduction into said socket member.

5. In a flash gun, a casing having an opening, and a generally tubular lamp receiving socket structure adapted to receive and hold a flash lamp of the type having a base formed with a circumferential recess and a locking flange adjacent the recess disposed within the casing at said opening comprising a socket member rigidly mounted on said casing and open forwardly in registration with said opening, said member being open rearwardly into the interior of said casing, a contact and ejector spring mounted within the casing and having a portion adjacent the rear opening of said socket member adapted to be engaged and compressed by the base of a lamp thrust into the front opening of said socket member, a latch lever rockably mounted on said socket member, said lever being formed with laterally extending side lugs and said socket member having fulcrum notches to receive said lugs, and said fulcrum notches being upwardly open and formed with inclined faces for guiding said lugs into said notches, spring means biasing said latch lever toward lamp base latching position on said socket member, detent and recess means on said latch member adapted to engage and interlock with the recess and flange on the base of a lamp thrust into the front opening of said socket member, and manually operable means accessible exteriorly of said casing for rocking said latch lever to lamp base release position against the force of said spring means to thereby permit said ejector spring to eject said lamp forwardly away from said casing.
